UNITED STATES PATENT OFFICE.

JAY NOBLE, OF ST. LOUIS, MISSOURI, ASSIGNOR OF ONE-HALF TO JAMES A. GUMERSELL, OF SAME PLACE.

RATCHET-DRILL.

SPECIFICATION forming part of Letters Patent No. 368,162, dated August 9, 1887.

Application filed March 26, 1887. Serial No. 232,530. (No model.)

To all whom it may concern:

Be it known that I, JAY NOBLE, of the city of St. Louis, in the State of Missouri, have invented a certain new and useful Improvement 5 in Ratchet-Drills, of which the following is a full, clear, and exact description, reference being had to the accompanying drawings, forming part of this specification, and in which—

Figure I is a perspective view of my improved drill, showing, also, part of a railway-rail and the frame in which the drill is held. Fig. II is an end view of the friction device. Fig. III is a section taken on line III III, Fig. IV. Fig. IV is a section taken on line IV IV, 15 Fig. III; and Fig. V is a section taken on line V V, Fig. III.

My invention relates to an automatic feed for ratchet-drills; and I have shown it in connection with a railway-rail and a suitable 20 frame for holding the drill up to the rail; but it may be used for other and various purposes.

My invention consists in features of novelty hereinafter fully described, and pointed out in the claims.

Referring to the drawings, 1 represents a railway-rail; 2, a frame engaging with the rail and provided with a rear support, 3, by which it is held up off the ties; 4, the drill; 5, the ratchet; 6, the handle of the ratchet, and 7 25 the feed-screw that centers against the back of the frame 2, as shown in Figs. III and V, and which enters the spindle or sleeve 8 of the drill, all of which parts are ordinary, and in them *per se* I claim no invention, my invention relating entirely to the attachment whereby the drill is fed automatically, and 30 which consists in securing a friction-wheel, 9, to the feed-screw 7, which turns with the screw. Loosely fitting on the feed-screw, preferably 35 outside of the friction-wheel 9, is a block or plate, 10, which may be held from end movement on the screw by means of a collar, 11, or it may be held by other suitable means which will allow the screw to turn independently of 40 it. This block 10 has an arm, 12, to which is secured on the under side a spring, 13, to bear against the periphery of the friction-wheel 9, and which may be adjusted to increase or di-

minish its pressure upon the roller by means of a set-screw, 14, passing through the arm 12. The 50 plate or block 10 has preferably also a projection, 16, which bears against the frame 2 to prevent the block or plate from being turned by the friction-wheel upon the spring 13. Other means could be provided to keep the 55 block from turning.

The operation is as follows: While the drill is cutting, the friction-wheel 9 and screw 7 turn with the drill, the friction between the wheel and the spring 13 not being sufficient to 60 keep the wheel from turning while sufficient pressure is on the drill to cause it to cut. As soon as the drill has cut for a short time, the backward end pressure of course decreases, and there not being sufficient friction between 65 the outer end of the screw 7 and the frame 2 to cause the wheel 9 to turn, under the pressure of the spring 13 the wheel stops, together with the feed-screw, and the spindle or sleeve 8 turns upon the feed-screw, advancing the 70 drill automatically. Then, as soon as the drill has been advanced a short distance, the friction of the spring 13 upon the wheel 9 is overcome and the screw 7 starts to turn with the sleeve or spindle 8 and the drill, and the feed 75 is thus automatically stopped, and thus the operation goes on, the drill being automatically fed, as necessary.

I claim as my invention—

1. In a ratchet-drill, the combination of the 80 feed-screw, friction-wheel on the screw, stationary plate, and a spring on said plate engaging the friction-wheel, substantially as and for the purpose set forth.

2. In a ratchet-drill, the combination of the 85 feed-screw, friction-wheel secured to the screw, stationary plate, and an adjustable spring on the plate bearing against the wheel, substantially as and for the purpose set forth.

3. In a ratchet-drill, in combination with 90 the feed-screw, a friction-wheel secured to the screw, a plate loosely mounted on the screw, a spring secured to the plate, a set-screw for adjusting the pressure of the spring, and means for keeping the plate from turning, substantially as set forth.

4. In a ratchet-drill, in combination with the set-screw, a friction-wheel secured to the screw, a plate, 10, loosely held on the screw, an arm, 12, on the plate, a spring, 13, secured to the arm, a set-screw, 14, passing through the arm and bearing against the spring, a projection, 16, on the plate, and a frame, 2, by

which the drill is supported and upon which the projection 16 bears, substantially as and for the purpose set forth.

JAY NOBLE.

In presence of—

GEO. H. KNIGHT,
EDW. S. KNIGHT.
